UNITED STATES PATENT OFFICE

THOMAS H. KINGSTON, OF WEST SOMERVILLE, MASSACHUSETTS, ASSIGNOR, BY MESNE ASSIGNMENTS, TO FRANK G. KINGSTON, OF SOMERVILLE, A. ROY KINGSTON, OF ARLINGTON, CHARLES C. PIMM, OF SOMERVILLE, AND MABEL G. KITCHEN, OF SOMERVILLE, MASSACHUSETTS, A PARTNERSHIP DOING BUSINESS AS BUILDERS' PATENT SCAFFOLDING COMPANY

LEDGER-BOARD CLAMP

Application filed January 26, 1927. Serial No. 163,787.

This invention relates to a clamp device and more particularly to a clamp device for use in securing ledger boards to uprights without the use of nails in erecting scaffolding for the construction of buildings.

It is an object of the invention to produce a sturdy serviceable device of few parts which may be rapidly applied to or removed from scaffolding in the erection or dismantling 10 thereof.

It is a further object of the invention to produce a clamp device wherein the parts thereof need not be separated, and thereafter assembled, for the purpose of applying or 15 removing it from scaffolding as in the past but which are of such construction and arrangement as to constitute a unit, certain parts of which are relatively movable but not separable from the other parts to permit 20 the said device to be applied to or removed from its operative position.

Another object of the invention is to produce a clamp device, portions of which are relatively movable but not separable having 25 locking means arranged to act in conjunction with pressure applying means to positively retain certain of the movable parts in firm co-operation when in use.

Other objects of the invention will be fully 30 understood from a description of the drawing and the claim hereinafter given.

Of the drawing.

Figure 1 represents an inside face view of 35 a portion of a scaffolding showing a portion of a ledger board secured to an upright by means of the present invention.

Figure 2 is a section taken on the line 2—2 of Figure 1.

Figure 3 is a detail of some of the parts 40 shown in Figure 2 but showing them moved to permit of the application of the clamp to the scaffolding or its removal therefrom.

Figure 4 is a perspective view of the lock 45 member used in connection with the pressure applying devices to retain certain of the movable parts of the clamp in firm co-operation when in use.

Figure 5 is a section on the line 5—5 of 50 Figure 1.

Like characters represent like parts

throughout the several figures of the drawing.

Referring to the drawing:

The drawing herewith illustrates a type of clamp for frictionally securing a board, such as a ledger board 10, to an upright or joist 11 as is required in erecting scaffolding for the construction of buildings and wherein the present clamp comprises a U shaped bolt member 12 having the screw threaded limbs 13 and 14, co-acting with the clamp member or bar 15 and provided with nuts 16 to clamp the board 10 and joist 11 together in a firm and substantially relatively immovable manner.

It is an object of the invention to so arrange the clamp that its parts may be moved, to adjust it to the scaffolding, but not separated for that purpose, and to that end the bar 15 and a nut 16 are passed onto the limb 13 whereupon the end of the limb is upset to form an enlargement 17 thereon which prevents the said nut and bar from being removed from the limb.

The limb 14 has a channel plate or lock member 18 and a nut 16 passed thereon before 75 its end is upset to form the enlargement 19 to prevent the removal of the said plate 18 and nut 16.

The bar 15 has a smooth bore hole therein through which the limb 13 passes and a notch 20 at its other end to engage the limb 14 by which means the said bar may be swung on the limb 13 to cause the notch 20 to engage the limb 14.

The plate 18 is provided with a smooth bore 85 hole 21 whereby it may be slid longitudinally of the limb 14 and has the side ribs 22 arranged to engage the bar 15 between them when the clamp is in place for use thus forming a locking member to prevent lateral swing 90 of the bar 15 and its disengagement from the limb 14.

To apply the clamp to the ledger board and upright, the nuts 16 will be turned on the screw threaded limbs 13 and 14, a sufficient 95 amount to permit the bolt member 12 and bar 15 to be moved away from each other to comfortably receive the upright and board between them and to permit the said bar to be swung past the plate 18 which will be slid 100

along the limb 14 with the nut 16 so that an opening will be formed between the limbs 13 and 14 for the passage of the clamp device into operative position.

5 When the device has been placed in position with the limbs 13 and 14 straddling the upright and board as seen in Figures 1 and 2 of the drawing, the bar 15 will be swung downwardly to engage the notch 20 with the limb 14, whereupon the plate 18 will be caused to engage the bar 15 so that the side ribs 22 will confine the bar between them after which the nuts 16 will be set up to tightly clamp the board to the upright.

10 15 It will be readily seen that the plate 18 effectively prevents the disengagement of the bar 15 and limb 14 when the device is in operative position.

15 It is known that clamp devices have been 20 used which had to be dismounted or partially so in order to apply or remove them from the scaffolding but it is not known that clamp devices of the class described have ever been used wherein the parts thereof were relatively movable but not separable or wherein locking means for certain of the parts was provided to co-act with pressure applying means to effectively prevent the accidental relative movement of those parts.

25 30 Having described the invention I claim:
A ledger board clamp consisting of a rod round in cross-section throughout its length and of substantially uniform diameter and which is U-shaped providing parallel limbs the extremity of each limb being threaded, a straight bar pivoted at one end to one limb and free to slide along such limb and having at its other end a notch extending crosswise and reaching to one edge of the bar and situated to move over or from the other limb when the bar is swung on its pivotal connection, a nut on the threaded part of each limb and a plate between the nut on the limb with which said notch cooperates having a lateral 40 projection situated to cover the open end of the slot and each of said limbs having its end enlarged to prevent the nut on the limb passing off the limb.

45 50 Signed by me at Clearwater, Florida, this 3rd day of December, 1926.

THOMAS H. KINGSTON.
